(57) **CLAIM**

We claim the ornamental design for a cat toy, as shown and described.

DESCRIPTION

FIG. 1 is a perspective view of the cat toy.

FIG. 2 is a top view thereof.

FIG. 3 is an exploded right side view thereof.

FIG. 4 is a left side view thereof.

FIG. 5 is a front view thereof.

FIG. 6 is a back view thereof.

FIG. 7 is a bottom view thereof; and,

FIG. 8 is a perspective view of the cat toy of FIG. 2.

The features shown in broken lines are for illustration only and depict portions of the cat toy that form no part of the claimed design.

1 Claim, 5 Drawing Sheets
